United States Patent Office.

JOSEPH KAYLOR, OF RESERVE TOWNSHIP, PENNSYLVANIA

Letters Patent No. 69,816, dated October 15, 1867.

IMPROVED MACHINE FOR MAKING PATCH-BOLTS.

The Schedule referred to in these Letters Patent and making part of the same.

TO ALL WHOM IT MAY CONCERN:

Be it known that I, JOSEPH KAYLOR, of Reserve township, in the county of Allegheny, and State of Pennsylvania, have invented a new and useful Improvement in Machine for Making Patch-Bolts; and I do hereby declare the following to be a full, clear, and exact description thereof, reference being had to the accompanying drawings, making a part of this specification, in which—

Figure 1 is a top view of my improved machine.

Figure 2 is a side view of the dies as they appear from a vertical plane passing through the line $z z$, fig. 1.

Figure 3 is a vertical section formed by a plane passing through the swage or upsetting tool in the line $y y$, fig. 1.

Figure 4 is a side view of one of the cams I employ, and

Figure 5 shows in perspective a patch-bolt which my machine is designed to make.

Like letters of reference designate like parts.

Such bolts usually consist of a head, x , of square or other polygonal cross-section, and slightly tapering toward the top, with a projecting shoulder, x' , bevelled on its under face, and terminating in a shank, x'' . The bevelled face of the shoulder x' usually rests in a countersink in the plate to be fastened, particularly when the bolt is used where its head is subject to the action of fire, as in the fire-box of a locomotive. In such places an ordinary bolt-head would soon be burned off, or be so injured by the action of the fire as to break off under a moderate strain. The patch-bolt is used by riveting the lower end of the shank x'' , or, in places where it cannot be conveniently riveted, it is chased, and used as a screw-bolt. In either case the bevel surface of the shoulder x' , resting in the countersink, gives it great efficiency in making a tight joint. The nature of my invention consists in the construction of a machine for making such bolts; that work having been heretofore done, I believe, entirely by hand.

To enable others skilled in the art to make and use my invention, I will proceed to describe its construction and mode of operation.

a is a substantial framework, to support the bed-plate b , and the machinery hereinafter to be described. Near one end of the machine are the dies $c c'$, both movable, or, as shown in the drawings, one, c , stationary, and the other, c' , movable. The inner faces of the dies $c c'$ are made with a cylindrical cavity, s , running in the direction of the swaging or upsetting movement yet to be described, and of the diameter of the rod from which the bolt is to be made. The dies $c c'$, at the inner end of the cavity s , have a conical cavity or countersink, s' , of the shape required to form the bevelled shoulder x' of the bolt. Resting on the bed-plate b , and operating in slides $d d'$, are sliding-bars e and f , one of which, f , is bevelled at the end next the movable die c' , so that its bevelled face operates as a wedge against a friction-roller, o , in the rear end of such die, to move it towards the stationary die c , and thus grip the rod. The other sliding-bar, e , carries a swage or upsetting tool, g , which is made with a socket, i , of the shape of the head x of the patch-bolt shown in fig. 5, the axis of the socket i and the direction of its motion being in a line with the axis of the cavity s . The sliding-bars $e f$ are at their other or rear ends bifurcated, to receive friction-rollers $o' o'$, against which play the cams $l l'$, which in turn are carried on and operated by the cam-shaft m , and to this the requisite motion is communicated in any of the ordinary ways. The cams $l l'$ are of the ordinary construction, but so shaped as to secure the movements yet to be described.

The bar to be formed into patch-bolts is introduced through a notch or aperture, n , in the frame a , and along the cavity s , until it strikes the base of the socket i , which latter, when drawn back, as shown in fig. 1, should be at such distance from the dies $c c'$ that a sufficient amount of metal may pass through between the dies $c c'$ to form the head x and shoulder x' . As soon as the rod or blank has reached this position, the cam l forces the wedge-ended sliding-bar f forward, so as to make the dies $c c'$ grip the rod securely. At the same time the knife v , attached to the movable die c' , severs the bolt or blank from the rod. The swaging-bar e is then driven forward by the cam l , and the base of the socket i being forced against the end of the blank staves it up or upsets it, so as to form the head x of the bolt in the socket i , and the bevelled shoulder x' between the end of the swage g and the bottom of the countersink s' . A part of the face of the cam l , fig. 4, is the arc of a circle, so that it is enabled to hold the die c' , and through it the manufactured bolt, in position, till the

swaging-bar *c* is withdrawn, which is effected by a spring, *c'*, or other equivalent means. As soon as this is done the cam *i'* releases the bar *f*, when it is carried back by the spring *f'*, the die *c* by the spring *c''*, and the bolt, being released from the dies by the hook-shaped strippers *r' r''* attached thereto, is discharged from the machine complete, and falls through an aperture, *n'*, in the bed-plate *b*.

In practical use the head *x* is an important part of the bolt, and is made of polygonal shape, in order to be operated by a wrench when used as a screw-bolt. It should also contain sufficient metal to form a full-sized rivet-head, after being screwed or riveted in position. The socket *i* should of course correspond to the shape desired in the head *x*.

The extensive use to which patch-bolts are applied, particularly in building locomotive and other engines, and the very considerable cost of forging them by hand, render my invention of great value, aside from its simplicity, cheapness, and practical efficiency as a machine. By its use patch-bolts can be manufactured cheaply, rapidly, and in abundant quantity, and in quality possessing the same elements of superiority which, as is well known, belong to other similar articles now manufactured by being pressed from hot iron. Such bolts thus made are also more uniform in size and shape, and consequently are better fitted for general manufacturing purposes.

What I claim as my invention, and desire to secure by Letters Patent, is—

In a machine for making patch-bolts, the arrangement and use of a pair of recessed dies, which, when brought together, form a cylindrical cavity for the shank and a conical cavity for the shoulder of the bolt, in combination with a swage or upsetting tool, having a cavity of polygonal cross-section for shaping the head, and at the same time upsetting the shoulder of the bolt in the conical cavity of the dies, constructed and arranged substantially in the manner and for the purposes hereinbefore set forth.

In testimony whereof I, the said JOSEPH KAYLOR, have hereunto set my hand.

JOSEPH KAYLOR.
